DESIGN FOR A BEVERAGE DISPENSER

Sol Jacobs, Elmwood Park, Ill., assignor to California Prune & Apricot Growers Association, San Jose, Calif., a corporation of California

Application July 29, 1933, Serial No. 48,881

Term of patent 14 years

To all whom it may concern:

Be it known that I, Sol Jacobs, a citizen of the United States, residing at Elmwood Park, in the county of Cook, State of Illinois, have invented a new, original, and ornamental Design for a Beverage Dispenser, of which the following is a specification, reference being had to the accompanying drawing, forming part thereof.

I claim:

The ornamental design for a beverage dispenser, as shown.

SOL JACOBS.
